UNITED STATES PATENT OFFICE

2,575,302

HYDRAULIC LOG BARKING MACHINE HAVING SUPPORT FOR LOG-ROTATING ROLLERS TILTABLE TO LATERALLY DISCHARGE THE LOG

Ernest C. Shaw, Milwaukee, Wis., assignor to Alis-Chalmers Manufacturing Company, Milwaukee, Wis., a corporation of Delaware

Application May 16, 1946, Serial No. 670,133

7 Claims. (Cl. 144—208)

1

The present invention relates to improvements in log handling and log barking machinery. More particularly the invention relates to an improved structure for handling a log and submitting the entire surface thereof to action of a barking tool or hydraulic barking jet.

It is already known to subject a log surface to the action of a hydraulic jet for bark removal and cleaning. It is also known to support a log, during cleaning, between spaced rotatable bed rolls parallel to the log axis, as shown in the United States patent to E. C. Shaw and W. C. Hagmaier, No. 2,338,136, issued January 4, 1944.

An object of the present invention is to provide an improved log handling device for feeding and discharging logs laterally to and from operative relation to a log treating tool.

Another object is to provide a housed hydraulic barker with lateral log feeding, positioning and discharging mechanism.

Still another object is to provide in a barker a tilttable parallel roll mechanism for handling a log in a manner to present its entire surface to action of a stream of water under the most favorable conditions for complete bark removal, and laterally discharge the same subsequent to treatment.

The above and still further objects and advantages can best be carried into practical effect as described hereinbelow with reference to the drawing in which:

Fig. 1 is a vertical cross sectional view on the line 1—1 of Fig. 2, of a log barker according to the invention; and

Fig. 2 is a longitudinal view of the barker of Fig. 1, as viewed from the left, with parts shown in section and broken away.

In the embodiment shown in the drawing, in which like reference characters indicate similar parts throughout the several views, the base 1 is provided with a water and bark disposal trough 2. On the rectangular base 1, a housing is erected having a side wall 3 with feed door 4, and a side wall 6 having a discharge door 7. Doors 4 and 7 are preferably hinged at their upper edges to swing inwardly and outwardly, respectively, as shown. End walls 8 and 9 of the housing may be provided, as shown, with suitable aligned bearings 11 and 12 in which is journaled a bed roll 13, having a shaft 14 and a log engaging surface 16, substantially cylindrical in form, extending approximately parallel to the sides of the housing. As shown in Fig. 1, conical centering surfaces 16' may be provided on the ends of roll 13 to limit axial movement of a log during treatment.

2

Pivoted on the housing or frame is a pair of arms 17, shown as pivotally mounted on shaft 14 of roll 13, at opposite ends of the housing. Each arm 17 is provided with a bearing 18 and a bearing 19 generally forming apices of a triangle with the bearing on shaft 14 constituting the third apex.

A second log supporting roll 21 has a shaft 22, journaled in bearings 18, and log engaging surfaces 23. Roll 21 is held parallel to roll 13 by supporting arms 17 which may or may not be connected by a rigid framework (not shown) extending parallel to rolls 13 and 21.

A connecting rod 24 connects bearings 19 with the piston rods of a pair of hydraulic servomotors, or other suitable mechanisms 26, operable by a manual control 27 to swing arms 17 equally on their pivots 14. This motion tilts the common plane of the rotational axes of rolls 13 and 21 through a definite range of inclination from zero, or horizontal, as shown in solid lines, to a maximum, as represented by the broken lines in Fig. 1, for a purpose to be described hereinabove.

The surfaces 16 and 23 of rolls 13 and 21 may be suitably knurled, fluted or otherwise roughened in any known manner to effect good frictional driving engagement with log surfaces. Such characteristic roughening of surfaces has been omitted from the drawing for the sake of simplicity, but is shown in United States Patent No. 2,338,136 referred to hereinabove.

At one side of the housing is a feed table. This table may consist of a suitable inclined skidway 28 provided with log detent or releasing mechanism 29 of known suitable type for serially releasing logs from the skidway, one at a time, under the control of an operator. The skidway 28 may have portions extending through door 4 into close proximity to the uppermost surface of roll 13, so that a log released by mechanism 29 will roll over roll 13 and, if roll 21 is in its uppermost position, will lodge in the crotch between the upper surfaces 16 and 23 of rolls 13 and 21, being held there by the force of gravity and rotated by frictional engagement with the roll surfaces 16 and 23 when one or both of the rolls 13 and/or 21 is turned. A driving mechanism such as a chain drive 31 from a motor (not shown) is provided for rotating one or both of these rolls 13 and/or 21.

Stop beam 32 may be provided in the housing to prevent logs fed to the machine from table 28 from rolling over roll 21 when being placed in the machine, and during operation.

A discharge table or skidway 34 has a portion

projecting through door 7 from adjacent roll 21 at a level below that of shaft 14, for receiving logs discharged from the crotch between the rolls by gravity dumping action when roll 21 is dropped by arms 17 to a suitable level. Such logs will pass, by gravity, through door 7 and down the suitably inclined skidway 34.

On the upper part of the housing, a pair of guide rods 36 and 36' support a carriage 37 movable longitudinally of the housing parallel to the rolls. Carriage 37 carries, in suitably keyed relation, a threaded shaft 38 engaging a rotatable nut 39 turned as by a gear pinion 41 of a nozzle control motor 42 mounted on the carriage. A suitable known limit switch arrangement (not shown) may be employed to automatically stop motor 42 at the limits of travel of shaft 38. Shaft 38 extends into the housing and carries a hydraulic nozzle 43 connected by a flexible conduit 44 with a source (not shown) of hydraulic fluid under high pressure. Conduit 44 may be partially supported by a roller carriage 46 running in a slot 47 in the housing.

Nozzle 43 is held in a manner to direct a jet of hydraulic fluid downwardly into the trough or crotch between the rolls 13 and 21 in such a manner as to impinge on the surface of an object such as a log or other roughly cylindrical body placed in the crotch. The nozzle tip may be positioned by shaft 38 at the most effective distance from the log surface regardless of log size, within a reasonable range of sizes.

The jet is horizontally movable in a vertical plane intermediate of and parallel to the roll axes by axial movement of the carriage 37, in such a manner as to clean the entire surface of a log or other body placed on the rolls and rotated thereby. Carriage 37 may be moved axially in any known suitable manner, as by providing a threaded connection between one of the guide rods 36' and the carriage 37, and providing a reversible variable speed drive 45 to rotate the threaded rod 36' relative to the carriage as shown in the drawing, Fig. 1. Motor 52 is shown as a source of power connected through drive 45.

Sliding rod 48 provided with a pair of fingers 49 may be mounted on the housing in the manner clearly shown in the drawing, with each finger 49 in a position to be engaged by a corresponding finger 51 on the carriage 37, when the carriage nears the ends of its axial travel. Rod 48 may be attached in operative relation to control drive 45 to reverse carriage travel at each end of its travel, and may also control a suitable known limit switch arrangement (not shown) to automatically stop motor 52 at each end of the carriage travel.

Since logs are fed, operated upon and discharged without axial movement the machine requires a minimum of floor space for operation.

A log released by mechanism 29 passes into the crotch between the surfaces of rolls 13 and 21. Roll surfaces 16 and 23 of rolls 13 and 21 are arranged in such a manner as to prevent logs above a predetermined minimum size from falling between the rolls. Rolls 13 and 21 act to support a log in parallel relation to the roll axes and to rotate the log, substantially on its longitudinal axis, in the plane of the jet path. The jet is moved longitudinally with relation to the log surface by carriage 37, or other suitable means, and removes a helical strip of bark (or cleans a helical strip of surface. The width of the helical strip cleaned or barked and the helical pitch established by the speed of carriage 37

in relation to the speed of rotation of the log on its axis, are so chosen as to result in a cleaning, or barking, of the entire log surface.

After treatment, the log, or other body, is discharged by the operator's manipulation of control 27, which actuates mechanism 26 to tilt the plane of support of bed rolls 13 and 21 until the log is dumped from the rolls under the influence of gravity and passes under stop beam 32, down skidway 34 and through door 7.

The housing prevents bark and water from splashing out into the woodroom. Bark and water fall into discharge trough 2 whence they may pass to screens or suitable disposal means (not shown).

It will be apparent that this invention provides a simple, effective, log handling mechanism for presenting a log to barking action of a hydraulic jet and due to the fact that logs are conveyed laterally to, through and from treating position, the machine will require less floor space for its operation than machines requiring longitudinal translation of logs.

While a specific embodiment is illustrated in the drawing and described in the specification, it is to be understood that the invention includes such modifications and equivalents as may readily occur to persons skilled in the art to which it appertains within the scope of the appended claims.

It is claimed and desired to secure by Letters Patent:

1. In a log handling device, a base, a feed table mounted on said base for holding a plurality of logs in parallel relation, means for serially feeding logs one by one laterally from one edge of said table, a pair of log supporting rolls operatively mounted adjacent said edge of said table and having their longitudinal axes in parallel spaced relation, means normally supporting said rolls for rotation with their longitudinal axes in a common substantially horizontal plane for receiving logs fed from said table, log stop means mounted on said base and having a portion closely spaced above the uppermost surface of one of said rolls when said rolls are positioned for receiving logs from said table, means associated with said roll support means for tilting the plane of support of said rolls about an axis parallel to said roll axes in a manner to lower said one roll with respect to said portion of said log stop means, and means for removing logs laterally from said rolls between said one roll and said portion of said log stop means when the plane of said roll axes is in tilted position.

2. In a log handling machine, a housing including side walls, a pair of bed rolls in said housing, support means for said rolls rotatably supporting said rolls with their longitudinal axes parallel in a common plane of support, means associated with said support means and actuatable to allow said plane of support to move downwardly from a substantially horizontal plane to a tilted position about a tilting axis parallel to said roll axes, a lateral feed door in one side wall of said housing above the level of said rolls when in their substantially horizontal position, a lateral discharge door in the opposite side wall of said housing below the level of said rolls when in their substantially horizontal position, said rolls forming a log receiving and supporting table for rotatably holding a log in parallel relation to said roll axes when in said substantially horizontal plane, and said rolls dumping said log

laterally through said discharge door when in said tilted position.

3. In a log handling device, a base, supporting structure mounted on said base, relatively stationary bearings in said structure, a log supporting roll rotatably carried in said bearings, a second log supporting roll cooperatively related to said first log supporting roll, roll supporting arms movably mounted on said base, bearings on said arms, said second roll being rotatably carried in the bearings of said arms with its axis of rotation in parallel relation to the axis of rotation of said first roll, means for rotating one of said rolls and means for simultaneously moving said arms to variably incline the plane of the axes of rotation of said rolls.

4. In a log handling machine, a housing including side walls, a pair of bed rolls in said housing, support means for said rolls rotatably supporting said rolls with their longitudinal axes parallel in a common plane of support, means associated with said support means and actuatable to tilt said plane of support between a substantially horizontal and a tilted position about a tilting axis parallel to said roll axes, a lateral feed door in one side wall of said housing above the level of said rolls when in their substantially horizontal position, a log stop means in said housing located slightly above the level of said rolls to prevent movement of a log laterally from said bed rolls on the side opposite said feed door, a lateral discharge door in the opposite side wall of said housing, said rolls forming a log receiving and supporting table for rotatably holding a log in parallel relation to said roll axes when in said substantially horizontal plane, and said rolls dumping said log laterally through said discharge door when in said tilted position.

5. In a log handling device, vertical supporting structure, bearings in said structure, a first log supporting roll rotatably carried in said bearings, a second log supporting roll cooperatively related to said first log supporting roll, roll supporting arms movably supported by said structure and swingable about the rotational axis of said first roll, bearings on said arms, said second roll being rotatably carried in the bearings of said arms with the axis of rotation in parallel relation to the axis of rotation of said first roll, means normally operative to support said second roll with its rotational axis in a common substantially horizontal plane with the rotational axis of said first roll, and means associated with said supporting means to cause said supporting means to become inoperative allowing said second roll to swing downwardly about said first roll to a position lower than said first roll to decline the plane of the axes of rotation of said rolls.

6. In a log handling machine, a housing including side walls, a pair of rotatable bed rolls in said housing, support means for said rolls nor-

mally supporting said rolls with their rotational axes parallel in a common substantially horizontal plane of support, said rolls forming a log receiving and supporting plane for rotatably holding a log in parallel relation to said roll axes when in a substantially horizontal plane, a lateral feed door in one side wall of said housing above the level of said rolls when in their substantially horizontal position, a lateral discharge door in the opposite side wall of said housing beneath the level of said rolls when in their substantially horizontal position, and means associated with said roll support means and actuatable to allow the roll adjacent said discharge door to remain parallel to the other roll but to move downwardly to the approximate level of said discharge door to tilt the log supporting plane of the said rolls and dump said log laterally through said discharge door.

20 7. In a log handling machine, a housing including side walls, a pair of rotatable bed rolls in said housing, support means for said rolls normally supporting said rolls with their rotational axes parallel in common substantially horizontal plane of support, said rolls forming a log receiving and supporting plane for rotatably holding a log in parallel relation to said roll axes when in a substantially horizontal plane, a lateral feed door in one side wall of said housing above the level of said rolls when in their substantially horizontal position, a log stop means in said housing located slightly above the level of said rolls to prevent movement of a log laterally from said bed rolls on the side opposite said feed door, a lateral discharge door in the opposite side wall of said housing beneath the level of said rolls when in their substantially horizontal position, and means associated with said roll support means and actuatable to allow the roll adjacent said discharge door to remain parallel to the other roll but to move downwardly to the approximate level of said discharge door to tilt the log supporting plane of the said rolls and dump said log laterally beneath said stop means and through said discharge door.
